to Joy Manufacturing Company, a corporation
of Pennsylvania

Application January 7, 1947, Serial No. 720,504

8 Claims. (Cl. 255—35)

1

This invention relates to rod spinning apparatus and more particularly to an improved fluid operated cable type rod spinning apparatus especially designed for use in uncoupling or connecting joints of the drill rod of a rotary oil well drill.

In the uncoupling or "breaking" of joints of a drill rod of a rotary oil well drill, the joints are commonly "broken" or loosened by a pair of power operated tongs, one of which serves to hold one joint part stationary while the other applies a powerful turning force to the other part to "break" the joint. Conversely, during tightening or "making" of the joints, the tongs are rearranged so that a powerful turning force is applied to the rod in a reverse manner to tighten or "make" the joint. After the joint is loosened by the tongs, it is desirable to turn rapidly the upper rod part to effect complete uncoupling or release, and the rod is also rapidly rotated or spun to effect coupling of the joint prior to tightening by the tongs. Heretofore it has been common practice to extend a cable or spinning line from an automatic cat head of the drill and to wrap or coil the intermediate portion of the cable or line around the rod part to be rotated, with the free end of the cable held taut by the operator. Since the cat head of the drill constantly rotates at a high speed during the spinning operation, and cannot be sensitively controlled, serious accidents sometimes result. Also the application of greater forces with the automatic cat head tends to gall the rod threads and oftentimes bend the drill rods so that proper engagement and disengagement of the threads is prevented. It is accordingly highly desirable to provide a rod spinning apparatus which will not only operate quickly to spin the rod to uncouple or connect the joint but also which may quickly be stopped when the joint is completely uncoupled or coupled so that possibility of injury to the operator is practically eliminated. It is also desirable to provide a rod spinning device which effects rapid turning of the rod part and also applies a uniform and an extremely powerful turning force to the rod part to be turned.

It is an object of the present invention to provide an improved rod spinning apparatus for an oil well drill which overcomes the disadvantages of previous known devices. Another object is to provide an improved rod spinning apparatus by which rapid turning of the rod part to be turned is effected in an improved manner. A further object is to provide an improved rod spinning

2

apparatus by which a smooth and extremely powerful turning force is applied to the rod part to be turned. A further object is to provide an improved cable type rod spinning apparatus which applies a uniform and powerful turning force to the rod part to be rotated and by which, when the joint is coupled or completely connected, drawing in of the cable may be quickly stopped so that the possibility of injury to the operator is substantially eliminated. A still further object is to provide an improved rod spinning apparatus of the fluid operated cable type. Another object is to provide an improved rod spinning apparatus embodying a speed multiplying, multiple reeve cable and pulley mechanism between the fluid actuated element of the fluid operated device and the portion of the cable which is wrapped about the rod, so that the cable portion is drawn in at a speed substantially higher than the given rate of travel of the fluid actuated element. Yet another object is to provide an improved rod spinning apparatus which is arranged and constructed in an improved manner. Other uses and advantages of the invention will, however, hereinafter more fully appear.

In the accompanying drawings, there is shown for purposes of illustration one form which the invention may assume in practice.

In these drawings:

Fig. 1 is a fragmentary end elevational view of an oil well drill equipped with a rod spinning apparatus constructed in accordance with a preferred illustrative embodiment of the invention.

Fig. 2 is a side elevational view of the drill and rod spinning apparatus shown in Fig. 1.

Fig. 3 is an enlarged detail end view illustrating the cable and pulley mechanism.

Fig. 4 is a vertical sectional view taken on line 4—4 of Fig. 3.

Fig. 5 is a cross-sectional view taken on line 5—5 of Fig. 3.

Fig. 6 is an enlarged horizontal sectional view taken substantially on line 6—6 of Fig. 1, with parts omitted to facilitate illustration.

Fig. 7 is a somewhat diagrammatic view illustrating the fluid system.

In this illustrative embodiment of the invention, the improved rod spinning apparatus is generally designated 1 and is associated with a portable rotary oil well drill, generally designated 2, although it will be evident that the spinning apparatus may be embodied in other types of drills.

The portable rotary drill 2 comprises a truck

frame 3 supported on rubber tired truck wheels 4 and carrying a platform 5 which supports a bed frame 6 for a conventional rotary table 7 for rotating a rod drill line 8 during the drilling operation. Mounted on the truck platform is a usual derrick mast 9 comprising upright side members 10, transverse frame members 11, and cross brace members 12, and the mast is pivoted at 13 on a base structure 14 carried by the truck platform to swing downwardly into a lowered transport position on the truck in a manner well known to those skilled in the art. The rod line 8 passes through and is adapted to be rotated during drilling by the rotary table 7, also in a well known manner, and comprises a plurality of rods 15 coupled together at 16 by a conventional coupling usually embodying coacting threaded parts on the adjacent rod-ends. The rods, at their joints, are tightly secured together so that considerable effort is necessary to effect loosening thereof. The rotary table 7 is driven through suitable transmission connections from conventional engines 17, 18 carried by the truck. In rotary drills of the character disclosed, a fluted or grooved grief stem or kelly is usually attached to the upper end of the rod line, and the rotary table 7 carries a usual driving bushing which engages the flutes or grooves of the grief stem so that the latter may be rotated as it slides through the table. When it is desired to add an additional rod to the rod line or to withdraw the rod line from the drill hole, the grief stem is detached from the rod line, and slips 18 are fitted in the table for supporting the rod line while it is being withdrawn from the hole. As the rod line is withdrawn, the joints 16 between the rods must be quickly disconnected, and after the joints are "broken" or loosened by the usual "make" and "break" tongs, it is desirable to spin rapidly the rod to be uncoupled in order to save time. Also during coupling of the rods, as the rod line is lowered into the hole, spinning in of the rods is similarly desirable.

Now referring to the improved spinning apparatus 1 for quickly completely uncoupling or for coupling the rod joints, it will be noted that extending vertically lengthwise of the derrick mast 9, when the latter is in its erect operative position shown, at one side thereof is a guideway 20 for a reciprocable pulley block 21 of a multiple reeve, speed multiplying, cable and pulley mechanism 22. This guideway, in this instance, comprises parallel guide rods 23, 23 rigidly attached at 24 at their upper ends to an upper frame member 25 preferably secured to a transverse frame member 11 of the derrick mast and at their lower ends at 26 to lugs 27 secured to a cross frame member 28 located at the mast pivot. Loosely surrounding the lower portions of these guides are stop sleeves 29 which provide bottom stops for the guide pulley block 21 in an obvious manner. The cable and pulley mechanism 22 further includes a relatively stationary top pulley block 30 attached by a bolt 31 to the upper frame member 25, and carrying a plurality of, herein, preferably three, rotatable pulleys 32, 33 and 34 suitably journaled in coaxial relation on a cross shaft 35 carried by the upper block frame 36. The lower guided pulley block is reciprocable longitudinally along the guide rods 23, 23 and carries a plurality of, herein preferably three, pulleys 37, 38 and 39 suitably journaled in coaxial relation on a cross shaft 40 carried by a lower block frame 41. It will be evident that the number of the pulleys and the arrangement of the pulley blocks

may be modified to provide different speed ratios to suit different operating conditions. The block frames have guide openings 42 through which the guide rods pass so that the pulley frame 41 of the lower block 21 serves in effect as a sliding cross head. Carried by a cross member 44 of the mast base structure 14 is a bracket 45 on which a guide pulley 46 is journaled, and this pulley is arranged in angular relation with respect to the pulleys of the pulley block. Attached to the bottom of the frame 36 of the upper pulley block 30 is an eyebolt 47, and connected to this eyebolt is one end of a spinning line or cable 48. This cable extends downwardly from its point of attachment with the upper pulley block around the pulley 37 of the lower pulley block, then extends upwardly and passes around the pulley 32 of the upper pulley block, and then extends downwardly about the pulley 38 of the lower block. The cable then extends upwardly around the pulley 33 of the upper block, then downwardly around the pulley 39 of the lower block, and then upwardly around the pulley 34 of the upper block and has its drop line extending downwardly from the rear side of the top pulley 34 to the guide pulley 46 on the mast base structure 14. The cable extends substantially horizontally from the guide pulley 46 to the rod line 8 wherein its intermediate portion is tightly wrapped around or coiled about, at 49, the rod to be rotated, and the free end of the cable extends outwardly at 50 in such manner as to be grasped and held taut by the operator during the rod spinning operation.

The improved spinning apparatus is fluid pressure operated, and there is a vertical fluid cylinder 51 secured at 52 at its lower end to the top of the table bed frame 6 and held at its upper end by a U-bolt 53 attached to the cross frame 44 of the mast base structure 14. Contained in this cylinder is a reciprocable piston 54 having its piston rod 55 extending upwardly and outwardly through the top cylinder head and coupled at 56 to the lower end of a cable connection 57, the latter in turn coupled at 58 to an eyebolt 59 attached to the bottom of the pulley frame 41 of the lower pulley block 21. The fluid system with which the cylinder is associated is shown somewhat diagrammatically in Fig. 7, and comprises a conventional valve block 60 secured to the top of the table bed frame at the side opposite from the spinning apparatus, and having its supply chamber connected by a conduit 61 to the discharge side of a conventional pump 62, herein a liquid pump, carried by the truck and having its intake connected to a suitable liquid tank 63. A discharge conduit 64 leads from the valve block 60 back to the tank. This valve block contains a conventional control valve 65 having a suitable operating handle 66 (Fig. 1). Leading from the valve block are conduits 67 and 68 connected to the opposite ends of the cylinder 51, as clearly shown, so that when the valve is properly positioned, the piston 54 may be moved under the influence of liquid under pressure in the cylinder either upwardly or downwardly as desired. The fluid system embodies conventional relief valves which may be adjusted in a known manner so that a predetermined pressure may be applied to the piston 54, which pressure is maintained substantially constant throughout the spinning operation.

The mode of use of the improved spinning apparatus will be clearly apparent from the description given. When the derrick mast 9 is in its erect operative position on the truck, as

shown in Figs. 1 and 2, the valve control handle 66 may be manipulated to move the valve 65 to effect supply of liquid under pressure through the conduit 68 to the lower end of the cylinder beneath the piston 54 to move the latter upwardly to its uppermost position. As the piston 54 moves upwardly, the operator may pull out on the spinning cable 48 to move the lower pulley block 21 upwardly along the guide rods 23, 23 to the raised position shown in Figs. 1 and 2, and the portion of the cable to be drawn in may then be coiled or wrapped tightly about the upper rod 15 to be rotated in the manner shown in Figs. 1, 2 and 6, and the free end of the cable is at that time grasped and held taut by the operator, who at that time may stand at the side of the rotary table remote from the spinning apparatus. The operator of the drill may then move the handle 66 to position the control valve to admit liquid under pressure through the conduit 67 to the upper end of the cylinder 51 to effect downward movement of the piston 54. Since the piston rod 55 is connected through the cable connection 57 with the lower pulley block 21, the latter is moved downwardly along the guide rods 23, and as the lower pulley block 21 is moved downwardly, the portion of the cable which is wrapped or coiled around the drill rod is drawn in at a speed substantially higher than the given rate of travel of the piston. Thus the rod to be rotated is turned or spun rapidly with respect to the adjacent rod completely to uncouple the joint 16 previously loosened by the tongs in a usual manner, and when the joint is uncoupled, the control valve may be quickly closed so that further drawing in of the spinning cable ceases, thus substantially eliminating the possibility of injury to the operator by preventing the hand of the operator which grasps the free end of the cable from becoming inadvertently drawn into the coil of the cable wrapped around the rod. When it is desired to couple a rod joint, the spinning cable is wrapped or coiled in a reverse manner about the upper rod to be rotated so that as the cable is rapidly drawn in by the piston through the cable and pulley mechanism, the rod is spun in a direction to couple the joint. After the joint has been coupled by the spinning in operation, it is tightened by the tongs in the usual manner. The above operations are repeated upon the coupling or uncoupling of each of the rod joints in an obvious manner. When the derrick mast is swung downwardly into its lowered transport position on the truck, the cable and pulley mechanism 22 and the guideway 20 for the lower pulley block 21 swings downwardly therewith, and the cable connection 57 between the piston rod and the movable pulley block permits the cable and pulley mechanism to assume a substantially horizontal position without detachment thereof and while the piston rod and cylinder remain vertical on the truck.

As a result of this invention, an improved rod spinning apparatus is provided whereby an extremely powerful turning force may be applied to the rod to uncouple the loosened joint in an extremely rapid manner. It will further be evident that by the provision of the improved rod spinning apparatus embodying the cable and pulley mechanism and the fluid cylinder and piston, a substantial speed multiplication is attained between the piston and the rod engaging portion of the cable to be drawn in so that the total length of the cable portion drawn in is many times the given distance of movement of the

piston. It will further be evident that by the provision of the fluid operated cable spinning apparatus of the type disclosed, spinning of the rod is rapidly effected to uncouple or couple the joint, and when the joint is completely uncoupled or coupled, the apparatus may be quickly stopped simply by closing the control valve, thereby reducing the possibility of serious accidents, which is present in known types of rod spinning equipment. It will further be evident that the improved spinning apparatus is of an extremely simple and compact design which may be readily embodied in a rotary oil well drill of a standard design. Other manners of use and advantages 10 of the invention will be clearly apparent to those skilled in the art.

While there is in this application specifically described one form which the invention may assume in practice, it will be understood that this 20 form of the same is shown for purposes of illustration and that the invention may be modified and embodied in various other forms without departing from its spirit or the scope of the appended claims.

25 What we claim as new and desire to secure by Letters Patent is:

1. In a rod spinning apparatus, the combination comprising a support carrying an upright frame structure, a vertical cylinder on said support and containing a reciprocable piston having its piston rod extending upwardly through the upper head of the cylinder, means carried by said frame structure providing a guideway extending vertically in alignment with the cylinder above 30 the latter, a multiple reeve cable and pulley mechanism comprising a stationary upper pulley block at the upper end of said guideway and a movable lower pulley block guided on said vertical guideway, a connection between said piston rod and said movable pulley block and extending along said guideway, a guide pulley on said support above said cylinder, said cable and pulley mechanism including a cable having one end held stationary and reeved about the pulleys of 35 said blocks, said cable at its other end extending downwardly from the upper pulley block and around said guide pulley, said cable extending substantially horizontally from said guide pulley and adapted to be coiled about a drill rod to be 40 spun with its free end held taut by the operator, and means for effecting fluid supply to said cylinder and said lower pulley block thereby to draw in the end of the cable coiled about the drill rod to 45 spin the latter.

2. In an apparatus of the character disclosed, the combination comprising a base and a derrick mast mounted thereon; a stationary vertical cylinder carried by the base and containing a reciprocable piston having its piston rod extending upwardly through the upper head of said cylinder, means on said derrick mast providing a vertical guideway extending in parallelism with said cylinder, a multiple reeve cable and pulley mechanism comprising a stationary upper pulley block supported by said mast and positioned by elements of said guideway-providing-means and a movable lower pulley block guided on said guideway, a connection between said piston rod and said lower pulley block, a guide pulley on the base near the upper end of said cylinder, said cable and pulley mechanism including a cable held stationary at one end and extending downwardly from the upper block and around said 50 guide pulley, said cable extending substantially 55

horizontally from said guide pulley and adapted to be coiled about a drill rod to be spun with its free end held taut by the operator, and means for effecting fluid supply to said cylinder to effect downward movement of said piston and said lower pulley block thereby to draw in the end of the cable coiled about the drill rod to spin the latter.

3. In an apparatus of the character disclosed, the combination comprising a base and a derrick mast pivotally mounted thereon, a stationary vertical cylinder carried by the base and containing a reciprocable piston having its piston rod extending upwardly through the upper head of said cylinder, means on said derrick mast providing a vertical guideway extending in alignment with said cylinder, a multiple reeve cable and pulley mechanism comprising a stationary upper pulley block supported by said mast and positioned by elements of said guideway-providing means, a movable lower pulley block guided on said guideway, a flexible connection between said piston rod and said lower pulley block, a guide pulley on the base near the upper end of said cylinder, said cable and pulley mechanism including a cable held stationary at one end and extending downwardly from the upper block and around said guide pulley, said cable extending substantially horizontally from said guide pulley and adapted to be coiled about a drill rod to be spun with its free end held taut by the operator, and means for effecting fluid supply to said cylinder to effect downward movement of said piston and said lower pulley block thereby to draw in the end of the cable coiled about the drill rod to spin the latter, said derrick mast being adapted to be swung downwardly on its pivot into a substantially horizontal transport position on the base, and said guideway-providing means and said cable and pulley mechanism swinging downwardly with said mast, said flexible connection between said piston rod and said lower pulley block permitting said cable and pulley mechanism to move into a substantially horizontal position without detachment of said flexible connection and while said piston rod and cylinder remain vertical.

4. In an apparatus of the character disclosed, the combination comprising a base and a derrick mast mounted thereon, and a rod spinning device carried by said base and at least in part supported by said mast comprising a stationary cylinder containing a reciprocable piston having its piston rod extending outwardly through one end of said cylinder, means on said mast providing a guideway, a multiple reeve cable and pulley mechanism comprising a stationary pulley block supported by said mast and positioned at one end of said guideway by elements of said guideway-providing means and a movable pulley block guided on said guideway, a connection between said piston rod and said movable pulley block, a guide pulley on said base, said cable and pulley mechanism including a cable held stationary at one end and reeved about the pulleys of said blocks, said cable extending downwardly from the stationary pulley block and around said guide pulley, said cable extending substantially horizontally from said guide pulley and adapted to be coiled about a drill rod to be spun with its free end held taut by the operator, and means for effecting fluid supply to said cylinder to effect movement of said piston and said movable pulley block thereby to draw in the

end of the cable coiled about the drill rod to spin the latter.

5. In an apparatus of the character disclosed, the combination comprising a base and a derrick mast pivotally mounted thereon and disposable in an upright position, and a rod spinning device carried by said base and in part supported by said mast comprising a stationary cylinder on said base and containing a reciprocable piston having its piston rod extending outwardly through one end of said cylinder, means on said mast providing a guideway, a multiple reeve cable and pulley mechanism comprising a stationary pulley block supported by said mast and a movable pulley block guided on said guideway, a flexible connection between said piston rod and said movable pulley block, a guide pulley on the base, said cable and pulley mechanism including a cable held stationary at one end and reeved about the pulleys of said blocks, said cable extending downwardly from the stationary pulley block and around said guide pulley, said cable extending substantially horizontally from said guide pulley and adapted to be coiled about a drill rod to be spun with its free end held taut by the operator, and means for effecting fluid supply to said cylinder to effect movement of said piston and said movable pulley block thereby to draw in the end of the cable coiled about the drill rod to spin the latter, said derrick mast being adapted to be swung downwardly on its pivot into a substantially horizontal position on the base, and said guideway-providing means and said cable and pulley mechanism swinging downwardly with said mast, said flexible connection permitting said cable and pulley mechanism to move into a substantially horizontal position with said mast without detachment of said flexible connection and while said piston rod and cylinder remain stationary on said base.

6. In an apparatus of the character disclosed, the combination comprising a base and an upright derrick mast mounted thereon, and a rod spinning device carried by said base and at least in part supported by said mast comprising a stationary cylinder containing a reciprocable piston having its piston rod extending outwardly through one end of said cylinder, means on said mast providing a vertical guideway and including parallel vertical guide rods, a multiple reeve cable and pulley mechanism comprising a stationary pulley block positioned at one end of said guideway by said parallel guide rods and a movable pulley block guided by said guide rods for movement along said guideway, a connection between said piston rod and said movable pulley block, a guide pulley on said base, said cable and pulley mechanism including a cable held stationary at one end and reeved about the pulleys of said blocks, said cable extending downwardly from the stationary pulley block and around said guide pulley, said cable extending substantially horizontally from said guide pulley and adapted to be coiled about a drill rod to be spun with its free end held taut by the operator, and means for effecting fluid supply to said cylinder to effect movement of said piston and said movable pulley block thereby to draw in the end of the cable coiled about the drill rod to spin the latter.

7. In an apparatus of the character disclosed, the combination comprising a base and a derrick mast pivotally mounted thereon and disposable in an upright position, and a rod spinning device carried by said base and in part supported

by said mast comprising a fluid operated device on said base and relative to which said mast is swingable, said fluid operated device including a movable fluid actuated element, a speed multiplying cable and pulley mechanism carried by said mast and including a movable pulley block, a guide pulley on said base, said cable and pulley mechanism including a cable extending downwardly around said guide pulley and substantially horizontally from said guide pulley and adapted to be coiled about a drill rod to be spun with its free end held taut by the operator, and a flexible connection between said movable pulley block and said fluid actuated element of said fluid operated device, said fluid actuated element upon fluid supply to said fluid operated device being movable to effect movement of said movable pulley block thereby to draw in the end of the cable coiled about the drill rod to spin the latter, said derrick mast being adapted to be 15 swung downwardly on its pivot into a substantially horizontal position on said base, and said cable and pulley mechanism swinging downwardly with said mast, said flexible connection permitting said cable and pulley mechanism to swing with said mast while said fluid operated device remains stationary on said base.

8. In a rod spinning apparatus adapted for use with oil well drills, the combination comprising a fluid operated device embodying relatively 20 movable cylinder and piston elements, means

5 providing a guideway comprising parallel guide rods, a stationary pulley block located at one end of said guideway and positioned by said guide rods, a movable pulley block guided by said guide rods of said guideway, and a spinning cable reeved about the pulleys of said blocks and having a portion to be drawn in which is adapted to be wrapped about a rod to be rotated, and an operative connection between the movable one 10 of said elements and said movable pulley block for moving the latter along said guide rods to effect drawing in of said cable portion to spin the rod.
